A. A. ADAMSON AND W. F. GRUPE,
METHOD OF PRODUCING RIM BOARDS,
APPLICATION FILED JUNE 17, 1918.

1,422,648.

Patented July 11, 1922.

UNITED STATES PATENT OFFICE.

ALLAN A. ADAMSON, OF BROOKLYN, NEW YORK, AND WILLIAM F. GRUPE, OF HUDSON HEIGHTS, NEW JERSEY.

METHOD OF PRODUCING RIM BOARDS.

1,422,648.

Specification of Letters Patent. Patented July 11, 1922.

Application filed June 17, 1918. Serial No. 240,463.

To all whom it may concern:

Be it known that we, ALLAN A. ADAMSON and WILLIAM F. GRUPE, citizens of the United States of America, residing at Brooklyn, county of Kings, State of New York, Hudson Heights, county of Bergen, State of New Jersey, have invented certain new and useful Improvements in Methods of Producing Rim Boards, of which the following is a specification.

The invention relates to a method of producing rim boards and more particularly to the method of producing rim boards for built-up paper boxes or containers, such rim boards having finish paper applied thereto.

The invention comprises directing paper board, or the equivalent and directing finish paper in proximity thereto, applying the finish paper to the board, with the use of adhesive and then cutting the board having the finish paper applied thereto, to the desired dimensions, thereby deriving a strip of proper length and width and having the finish paper applied to certain faces and for the extent as may be desired for the particular use for which the finished board is to be applied.

The invention is particularly useful in the making of paper containers, such as cigarette boxes, usually formed of a tray having a neck inserted therein and a cover adapted to fit the neck.

As an example of one manner of carrying out the invention, we now describe the production of a rim board suitable to be combined with a bottom to form a tray; however, it will be understood that such rim board is also capable of being combined with the top to form the cover and for the sake of brevity, it will be understood that the term "rim" as employed hereinafter, applies to that of the cover as well as to that of the tray, and that the term "bottom" applies also to the top.

In the usual rim of such paper container, the finish paper is applied to a flat face, turned over at a longitudinal edge and affixed to such portion of the opposite flat face as may be desired. The finish paper also extends laterally of the strip to form an extension having its greater dimension in the direction of the length of the strip. Such extension, upon folding the strip to produce the rim, is affixed to the bottom

and serves to hold the bottom to the rim, 55 and thus hold the tray parts together.

For such purpose, the board may be supplied from a reel of indefinite length, and similarly the finish paper, the width of the latter providing for the desired width of the 60 lateral extension. The board and finish paper are brought together and the finish paper applied to the board, and affixed thereto by the use of any suitable adhesive.

Further features and objects of the invention will be more fully understood from the following description and the accompanying drawings, in which—

Fig. 1 is a diagrammatic perspective view, showing the step of applying the finish paper to the board strip;

Fig. 2 is a top plan view, showing a portion of the indefinite length of board strip having the finish paper applied thereto and a circular knife for severing to proper 75 lengths;

Fig. 3 is an end view of the severed strip having the finish paper co-extensive with the strip; and

Fig. 4 is a top plan view of the completed 80 tray of a paper box, embodying the strip length shown in Fig. 3.

Referring to Fig. 1, the board 1 is shown fed from the reel 2, and the finish paper 3 similarly fed from the reel 4. The indefinite length of finish paper 3 is applied, with the use of adhesive, to the indefinite length of board 1, while in flat position, as by means of any approved shoe 5, or equivalent, for folding over in the desired relation. Preferably, the finish paper 1 is cut or provided of a width relative to that of the board to provide the lateral extension 6, when the paper is folded over at the edge 7 and covers such portion of the face 8 of the 95 board 1 as may be desired.

The combined indefinite length of board and finish paper applied thereto is run in flat position toward the circular cutter 9, as indicated in Fig. 2, or equivalent, and severed thereby in a plane substantially perpendicular to the flat faces 8, 10 of the board, yielding a strip 11 of board having the finish paper applied thereto. The length of the strip 11 is determined by the perimeter of the strip when folded and positioned as a part of the article in which it is to be incorporated.

In Fig. 4, we have indicated such strip 11 forming the rim of a tray 13 of a built-up paper box such as a cigarette box.

As will be noted from Figs. 2 and 3, the severed strip 11 of board with the finish paper applied thereto, has its two opposite ends 14, 15 "squared" and the opposite edges at both ends of the finish paper 3 extending substantially co-incident with the "squared" ends 14, 15.

The resulting product 13, such as a tray of a box embodies the severed strip 11 as its rim, the ends 14, 15, forming butt ends and the extension 6 of the finish paper being applied to the four peripheral portions of the bottom piece 16, thereby holding the rim 11 in position, and the ends 14, 15 immediately abutting one another. The extension 6 of the finish paper serves also to finish the face of the bottom piece 16.

The severing of the indefinite length of rim strip effects clean ends of the combined board and finish paper, affording a product of a high degree of artistic appearance. The severing, to provide for the butt ends of the strips, is performed rapidly and accurately, and entirely eliminates waste.

The rim of the tray thus formed possesses the full required degree of strength.

The cutting may be performed manually, but for attaining speed the cutting is usually performed by means of a mechanically operated, severing or punching device.

For obtaining a strip having the straight ends, the severing is expeditiously performed by means of a power operated, circular knife, such as described in our co-pending application Serial No. 240,426, filed June 17, 1918, entitled Rim boards.

Our invention is advantageously carried out by feeding the board from a reel and similarly feeding the finish paper from a reel.

Such straight end strip may be utilized in the forming of the rim as a butt strip, i. e., the opposite ends upon folding the strip abutting one another, in which case the length of the strip is approximately the perimeter of the folded rim; or such straight ended strip may be utilized as a lap strip, i. e., the opposite end portions of the strip upon folding the striplapping one another, in which case the length of the strip exceeds the perimeter of the rim by the extent of the lap.

The invention is advantageous in that the operation of applying the continuous length of finish paper to continuous length of the board reduces the period of the stage of affixing one to the other and also reduces the operation of severing, in that both the board and the finish paper are cut at the same time. The invention effects the further and important advantage of producing strips hav-

ing finish paper affixed thereto but free from any tab or tabs of the finish paper, in other words, the finished strip is without any tab of the finish paper at either of its ends. By reason of this important feature of our invention, the production of the box parts is materially expedited since our invention entirely overcomes the delay due to the interference of the prior art tax strips in obstructing the parts of the box producer, conveying adhesive to the parts and by being torn off and dropping in the box producer.

The invention results in materially reducing the number of defectively formed boxes and box parts.

Whereas we have described our invention by reference to specific methods, it will be understood that many changes and modifications may be made without departing from the invention as defined by the appended claims.

We claim.

1. The method of forming built-up rectangular boxes, comprising feeding a continuous length of board in substantially flat relation, feeding a continuous length of finish paper in approximate relation to the fed flat length of board, affixing the finish paper to the board while in flat relation and providing an extension of the finish paper projecting laterally of the board length, severing the length of the board having the finish paper affixed thereto while in flat relation and of a length equal to the perimeter of the box part, discharging the severed length of board having the finish paper affixed thereto in flat relation and thereafter folding the severed length to form the box part and affixing the extension of the finish paper to contiguous parts of the box.

2. The method of forming built-up rectangular boxes, comprising feeding a continuous length of board in substantially flat relation, feeding a continuous length of finish paper in approximate relation to the fed flat length of board, affixing the finish paper to the board while in flat relation and providing an extension of the finish paper projecting laterally of the board length, severing the length of the board having the finish paper affixed thereto while in flat relation and of a length equal to the perimeter of the box part, discharging the severed length of board having the finish paper affixed thereto in flat relation and thereafter folding the severed length with its ends in butt relation to form the box part, and affixing the extension of the finish paper to contiguous parts of the box.

In testimony whereof we have signed this specification this 11th day of June, 1918.

ALLAN A. ADAMSON.
WILLIAM F. GRUPE.
